STARTING CATHODE FOR ELECTROLYTIC REFINING OF COPPER AND OTHER METALS

Application filed November 15, 1928. Serial No. 319,708.

In refining copper electrolytically, the copper to be refined is cast in plate form as anodes which are suspended in electrolytic tanks in alternation with cathodes in plate form, the electrolysis dissolving copper from the anodes and depositing it on the cathodes, while the insoluble impurities collect at the bottom of the vat in the form of anode mud or slime. For the starting of this process it is customary to use thin plates or sheets of deposited copper which are stripped from a rolled plate on which the deposit is made, and are then straightened to bring them to a flat or plane surface, and are suspended in the electrolytic tank by hanging them on copper conducting rods. They are usually suspended by means of loops which embrace the rods and are riveted to the upper edge portion of the cathode sheets. Such cathode sheets are known as starting sheets or starting cathodes. They are thin sheets of deposited copper which have been flattened to as close an approximation as possible to a vertical plane, but which have not sufficient stiffness to keep them rigidly in such planes, and are subject during the electrolytic process to some distortion by reason of temperature variations and other disturbing conditions within the electrolytic tank.

The present invention provides an improved construction of starting sheet which is corrugated in such manner as to impart to it a high degree of stiffness or rigidity such as to prevent warping, curling, or other distortion during electrolysis. The suspending and conducting loops for connecting the cathode plates to their suspending cross-bars are attached to the sheets by a forming and swaging or riveting operation which is advantageously performed at the same stroke of the press by which the corrugating is effected.

The accompanying drawings show the preferred construction of starting sheet according to this invention:

Figure 1 is an elevation of the sheet with its bar and hangers, only a portion of the corrugations being shown.

Fig. 2 is a transverse section on the line 2—2 in Fig. 1.

Fig. 3 is a fragmentary front elevation, being an enlargement of one corner of Fig. 1.

Fig. 4 is a vertical section of Fig. 3 on the line 4—4 therein.

Fig. 5 is a vertical section of the upper part 55 of the sheet on the line 5—5 in Fig. 1.

Fig. 6 is a vertical section on the line 6—6 in Fig. 1.

In the drawing, A is the starting sheet or starting cathode, B B are its suspending 60 loops, and C is the usual copper bar from which the plate is hung, and which serves as the means of electrolytically connecting it with the conducting bars or bus bars of the tank.

Practically the entire surface of the sheet is formed with corrugations *a a*, which are here shown as vertical, being supplemented by horizontal corrugations *b* above, and *c* beneath. These corrugations are preferably 70 of about the proportions shown. They serve to stiffen the entire sheet and impart to it a high degree of rigidity or resistance to bending in all directions. The lower corrugations *c* are best made of diminishing depth, 75 as shown in Fig. 4, so that they afford very little approach to horizontal surfaces on which slimes might adhere, it being desirable to cause all the anode mud or slime carrying the precious metals to precipitate to the bottom of the tank beneath the electrodes.

The upper corrugations *b* are interrupted at two points conveniently separated to afford plain surfaces for the attachment of the suspending loops B B. These loops are 85 strips of copper bent together and united to the plate by any suitable forming and swaging or riveting operation. In the construction shown, the plate is punched with holes and the strips are driven at *d* through these holes 90 and expanded and clinched down at *e* in the manner of a hollow eyelet, or by any other swaging operation. The closed loops embrace the copper bar C tightly, as usual, so that the bar serves both as a support and an 95 electric conductor.

Practical use of these corrugated starting sheets has demonstrated that they have important and valuable advantages. The ordinary flat starting sheets require to be "flopped" 100

after a run of about 36 hours; this requires that the plates be taken out of the vat singly, placed on an inclined wooden plane, and straightened by pounding with wooden beaters, after which they are replaced in the tank and the deposition is continued. This flopping is entirely avoided by the use of the corrugated sheets, which have such inherent stiffness as to preserve their original flat plane during the entire period of electrodeposition. Other advantages are that labor is saved in the straightening or flattening of the sheets, labor is saved in the hanging of the sheets, clean contacts are insured throughout the period of deposition; transfer resistance is equalized, resulting in uniformity of voltage; higher ampere efficiency is attained; the sheets afford an increased depositing area; a greater yield in copper per tank day is obtained; any small nodules formed on the original starting sheets are minimized in the process of corrugating, and the handling of the finished cathodes is economized.

While the invention is principally useful for copper refining, it is available in any electrolytic refining where a starting sheet is used, of the same metal which is deposited from the electrolyte on the cathode, as for lead, nickel, etc.

30 We claim as our invention:—

1. A cathode starting sheet for electrolytic refining of metal, having its surface varied by parallel corrugations extending in different directions.
- 35 2. A cathode starting sheet for electrolytic refining of metal, having its surface varied by parallel corrugations extending both vertically and horizontally.
3. A cathode starting sheet for electrolytic refining of metal, having its surface varied by parallel corrugations occupying the main surface area, and marginal corrugations at right angles thereto.
- 40 4. A cathode starting sheet for electrolytic refining of metal, having its upper portion stiffened by horizontal parallel corrugations and having vertical parallel corrugations below the horizontal corrugations and suspension loops applied to portions of the sheet
- 50 50 where the horizontal corrugations are interrupted.

55 5. A cathode starting sheet for electrolytic refining of metal, having a conducting bar and suspension loops embracing said bar and fastened to the plate, the surface of the plate, except where engaged by said loops, stiffened by parallel corrugations extending in different directions.

In witness whereof, we have hereunto
60 signed our names.
